UNITED STATES PATENT OFFICE.

LOUIS SCHERZ AND EMIL SCHERZ, OF WILKES-BARRE, PENNSYLVANIA.

EYE PROTECTOR.

Application filed April 28, 1926. Serial No. 105,176.

Workmen engaged in avocations such as coal mining, glass working, metal founding and the like, resulting in filling the air with small particles frequently suffer injury and 5 experience annoyance and inconvenience by such particles lodging in or striking the eyes. Hence the present invention aims to provide an article for protecting the eyes, which is always conveniently at hand to be 10 adjusted into operative position when required, and shiftable into inoperative position to be out of the way when not required for protection.

In accordance with the invention, the 15 protector is connected to a miner's cap or other form of head covering, by elastic means, such as webbing, in a manner to hold the protector against the face in front of the eyes, or against the cap so as to be out of the 20 way when not required for service.

While the drawings illustrate a preferred 25 embodiment of the invention, it is to be understood that in adapting the means to meet specific needs and requirements, the design 30 may be varied, and such other changes in the minor details of construction may be resorted to within the scope of the invention, as claimed, without departing from the spirit thereof.

For a full understanding of the invention 35 and the merits thereof, reference is to be had to the following description and the drawings hereto attached, in which,—

Figure 1 is a side view illustrative of an 40 embodiment of the invention, the full lines showing the protector in operative position, and the dotted lines in inoperative position,

Figure 2 is a front view showing the 45 protector in active position,

Figure 3 is an enlarged longitudinal sectional view of one of the members of the 50 protector, and

Figure 4 is a transverse sectional view of a 55 member of the protector.

Corresponding and like parts are referred 60 to in the following description and designated in the several views of the drawings by like reference characters.

The numeral 1 designates a miner's cap 65 which is illustrated to demonstrate the application of the invention. The protector is connected to the cap, or other form of head covering, by means of elastics 2, which may consist of webbing or other suitable means.

The elastic connections 2 prevent displacement of the protector and insure the same being at hand for instant use when required. The full lines in Figures 1 and 2 show the protector in operative or active position, 60 whereas the dotted lines in Figure 1 show the protector held against the crown of the cap, so as to be out of the way when not required to protect the eyes, but in position for instant service, should occasion arise. 65 The protector is shaped to fit close against the face, without causing discomfort, while, at the same time, providing ample room for vision and ventilation.

In the preferable construction, the protector 70 comprises similar sections or members which are detachably connected, each of the members being connected to the cap by means of an elastic 2. The sections or members are adapted to overlap at their inner 75 or meeting ends and are connected by means of separable fastenings of the stud and socket type. Each of the members or sections of the protector is elongated and outwardly 80 bulged, as indicated most clearly in Figures 85 3 and 4, the marginal portion being of such shape as to obtain a close fit against the face so as to exclude foreign matter from the eyes. The body portion 3 of the protector 90 preferably consists of wire gauze, pressed 95 into concavo-convex shape, and having its edge reinforced by means of a binding 4 of leather, or other suitable material. The middle portion of the protector corresponding 100 to the overlapping ends is constricted 105 so as to obtain a snug and neat fit across the nose, as indicated most clearly in Figures 1 and 2 of the drawings. The cap is provided 110 with one element 5 of the separable fastening and each of the members of the protector is provided with the companion element 6 of the fastener. When the protector is not required for actual service, the members or sections are disconnected and each of the members is connected to the cap by engaging 100 the element 6 with the element 5, substantially as indicated by the dotted lines in Figure 1. It will thus be understood that the protector is in position for instant use when required. The members may be quickly 105 disconnected from the crown of the cap and connected by engaging the elements 5 and 6 of the fastener, and when the cap is placed in position upon the head and the protector adjusted to cover the eyes, as in- 110

dicated in Figures 1 and 2, it is retained in place by means of the elastic connections 2 as will be readily appreciated.

Having thus described the invention, we 5 claim:

1. The combination with a cap, of an eye 10 protector comprising separable sections, an elastic connecting the outer end of each section with a side of the cap and complementary fastening elements, on the crown of the cap and at the inner ends of the said sections for securing the latter to the cap when detached or connecting the sections when the device

is placed against the face to protect the eyes.

2. In combination with a cap, a sectional 15 eye protector, an elastic connecting each of the sections with the cap and separable fastening means having companion elements applied to the sections and cap, whereby the sections may be connected to one another or 20 to the cap, as required.

In testimony whereof we affix our signatures.

LOUIS SCHERZ. [L. S.]
EMIL SCHERZ. [L. S.]
